UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

RECEPTACLE.

1,257,614.

Specification of Letters Patent. Patented Feb. 26, 1918.

Application filed May 7, 1917. Serial No. 166,881.

To all whom it may concern:

Be it known that I, JOSEPH KOMOROUS, a citizen of the United States, residing at Chicago, in the county of Cook and State of Illinois, have invented a new and useful Improvement in Receptacles, of which the following is a specification.

My invention relates, more particularly, to receptacles for receiving relatively heavy articles such as coins, of the variety involving a curved side-wall usually cylindrical, and cover-sections one of which is permanently united with the said side-wall; and my primary object is to provide for the uniting of the side-wall and the bottom of the receptacle, by novel and simple means and in a manner whereby these parts will be rigidly and firmly held together.

Referring to the accompanying drawing: Figure 1 is a view in vertical sectional elevation of a bank constructed in accordance with my invention.

Fig. 2 is a section taken at the line 2 on Fig. 1 and viewed in the direction of the arrow.

Fig. 3 is a bottom plan view of the removable cover-section of the bank.

Fig. 4 is a view in side elevation of the side-wall of the bank.

Fig. 5 is a fractional plan view of one of the disks forming the bottom cover-section.

Fig. 6 is a broken plan view of the bottom cover-section with parts thereof broken away; and

Fig. 7, an enlarged broken view showing the parts of Figs. 4 and 5 united.

I have illustrated my invention as incorporated in a pocket-bank structure of a type employing a cylindrical side-wall 8, a bottom-forming disk 9 united with the side-wall 8 as hereinafter described, and cover-sections 10 and 11, the section 10 being permanently secured to the side-wall 8 and the top section 11 removable and replaceable thereon.

The bottom section 10 in the particular construction illustrated is formed of a disk 13 having an up-turned annular flange 14 crimped into engagement with the lower outwardly flared end of the side-wall 8 with a covering 15 of celluloid, or other suitable covering material, extending over the face of the disk 13 and up over the flange 14 thereof and into a position in which it is interposed between the said flange and the side-wall 8. The cover-disk 11 is formed of

an inner disk 16 and an outer disk 17 flanged at its periphery as represented at 18, the outer disk being crimped at its flange 18 about the disk 16, with a covering, represented at 19 and which may be of celluloid, or any other suitable material, extending over the top surface of the disk 17 and between the flange 18 and the edge of the disk 16, the cover-section 11 being releasably held in place as hereinafter described.

In constructing the receptacle in accordance with my invention the lower edge of the band forming the side-wall 8 is provided with teeth 20 spaced apart as shown and the disk 9 is likewise provided about its periphery with teeth 21, these teeth, which mesh with each other as shown, presenting by the spaces between them, recesses about the lower edge of the side-wall 8 and the periphery of the disk 9. In the particular construction illustrated it is intended that the teeth 20 be bent to hold these two parts together and in accordance therewith the teeth 20 are bent inwardly to overlap the bottom surface of the disk 9 as illustrated in Figs. 1 and 6. By so constructing this part of the receptacle the parts are very securely interlocked together and held against separation even when subjected to severe stress as for example, should the receptacle be dropped upon the ground when filled with relatively heavy articles such as coins, thus danger of spilling of the coins from the receptacle, and breaking into the bank by prying off the bottom, is greatly minimized, this feature being of especial importance when the bottom of the receptacle is celluloid covered, inasmuch as the engagement between the band 8 and the disk 10 is celluloid to metal, which does not permit of the maximum gripping of the disk to the side-wall.

Another feature of my improvement consists of the interlocking of the celluloid covering 15 with the portion of the structure 100 engaged by the disk 13 to augment the grip of these parts one to the other and prevent relative rotation thereof. This feature is of importance in a structure wherein it is desired that certain parts of the structure be held against relative rotation upon rotating another part thereof, as for example in a bank structure wherein the parts are so constructed and arranged that the separation of the parts of the structure to open the bank,

renders necessary the relative movement of parts thereof to a predetermined position against resistance. An example of such a structure is shown in the drawings wherein the cover-section 11 must be rotated upon the side-wall 8 to a certain position before the cover can be removed, the cover being provided with depending lugs 22 adapted to register, when in one position, with recesses 23 in a flange 24 provided on the upper end of the side-wall 8 and interlock with the flange 24 when moved out of registration with said recesses, these lugs being notched as represented at 25 for engagement with the spring catch devices 26 which automatically spring into the notches 25 upon rotating the cover-section 11 to a position in which the lugs 22 are out of registration with the recesses 23, and may be released from engagement with the lugs 22 by the insertion of a suitable tool into the interior of the bank through the coin slot 27. The recesses 28 provided between the teeth 21 on the disk 9 are preferably deeper than the thickness of the metal forming the teeth 20 and thus when the teeth 20 are turned inwardly to overlap the side of the disk 9 a series of depressions are formed about the periphery of this disk as shown in Fig. 6. These depressions are of such depth that in the process of crimping the cover 10 in position on the side-wall 8 as stated the celluloid bulges into the said depressions as indicated at 29 thus interlocking with the disk 9 and firmly holding this covered disk 13 to the side-wall, to such a degree that it will not turn on the side-wall 8 under the stresses to which it is ordinarily subjected in the operation of relatively rotating the parts of the structure to open the bank or lock its parts together, this interlocking effect being augmented by the projection of the teeth 20 below the plane in which the under surface overlapped by these teeth, extends, depending upon the thickness of metal forming these teeth.

While I have illustrated and described a particular construction in which my invention is embodied I do not wish to be understood as intending to limit it thereto, as the same may be variously modified and altered

without departing from the spirit of my invention, it being my intention to claim my invention as fully and completely as the prior state of the art will permit.

55

What I claim as new, and desire to secure by Letters Patent, is:

1. In a receptacle, the combination of a curved side-wall-forming member having an outwardly flared end and a disk member located at the flared end of said side-wall forming member, one of said members containing recesses and the other thereof provided with teeth extending into said recesses and bent into overlapping position relative to the other of said members, and a second disk covering said first-named disk and having a flange crimped into interlocking relation with the flared portion of said side-wall-forming member.

60

2. In a receptacle, the combination of a curved side-wall and a disk at one end of said side-wall, said disk containing recesses in its periphery and said side-wall having teeth extending into said recesses and bent into overlapping position relative to the said disk, said recesses being deeper than the thickness of the metal forming said teeth to provide a series of laterally-extending projections about the periphery of said disk, and a second disk having a flange with a covering of celluloid, or the like material, extending over said last-named disk and about said flange, said second disk being held to said side-wall by engagement of the flange with said side-wall, with said covering interposed therebetween.

70

3. In a receptacle, the combination of a curved side-wall-forming member, a disk-member at the end of said first-named member, means interlocking said members together and presenting a series of depressions, and a second disk having a flange with a covering of celluloid, or the like material, extending over said second disk and about said flange, said second disk having its flange crimped to hold said second disk to said members, with the celluloid interposed therebetween and between said flange and projecting into interlocking relation with the said depressions.
